BOX FOR DISPLAYING CONTENTS

Marcus M. Tierney, St. Paul, Minn.

Application August 19, 1946, Serial No. 691,477

13 Claims. (Cl. 229—17)

1

This invention relates to a container or box adapted to contain various forms of merchandise and while the box could contain many different kinds of articles, it particularly is designed to contain screws, small nails, tacks and similar articles of hardware, etc. It is desirable to have the different kinds of articles, such as different sizes of screws, nails, etc. visible and readily accessible. If the container is closed, as is now the common practice, it is necessary to take time to open the container to show the contents or to remove some of the contents.

It is an object of this invention to provide a container having a bottom portion which can readily be swung to expose an opening in the box through which the contents are visible and accessible, together with means for holding said bottom portion in swung position.

It is a further object of the invention to provide such a container or box as set forth in the preceding paragraph, said bottom portion having a front portion extending upwardly therefrom which is also swingable outwardly to enlarge said opening and further expose the contents of the container and to make them more accessible, together with means for holding said front portion in the desired position.

It is another object of the invention to provide a box formed of sheet material and being rectangular in transverse cross section, the same having a bottom swingable about one edge thereof, said box having an opening at the side opposite said edge adjacent said bottom, said bottom having side portions extending upwardly therefrom and having a front portion extending upwardly therefrom, said front portion being adapted to close said opening when the box is in closed position and being swingable about the edge of said bottom opposite said first mentioned edge, together with means for holding said bottom and front portions in the desired position to which they are swung.

It is more specifically an object of the invention to provide a container in the form of a box folded from a blank of sheet material and being rectangular in transverse cross section, said box having a bottom swingable about one edge thereof, said box having an opening adjacent said bottom at the side opposite said edge, said bottom having side portions extending upwardly therefrom and disposed at the sides of said box and having a front portion extending upwardly therefrom, said front portion being adapted to close said opening when the box is in closed position, and being swingable forwardly about the

2

edge of said bottom opposite said first mentioned edge, said front portion having parts at the sides thereof disposed along the sides of said box, together with means preferably in the form of bands disposed at opposite sides of said box engageable by said side portions of said bottom and said parts of said front portion to hold said bottom and front portions respectively in the desired position with said opening exposed.

It is still further an object of the invention to provide a novel blank for such a box as above described.

These and other objects and advantages of the invention will be fully set forth in the following description made in connection with the accompanying drawings in which like reference characters refer to similar parts throughout the several views and in which:

Fig. 1 is a diagonal view of the box forming this invention;

Fig. 2 is a horizontal section taken on line 2—2 of Fig. 1, as indicated by the arrows;

Fig. 3 is a plan view of a blank used in making the box;

Fig. 4 is a view in side elevation of the box;

Fig. 5 is a vertical section taken on line 5—5 of Fig. 2;

Fig. 6 is a vertical section similar to Fig. 5 showing the parts in different positions; and

Fig. 7 is a view similar to Fig. 5 showing the parts in still further different positions.

Referring to the drawings, a box 10 of general parallelopiped form and thus being rectangular in transverse cross section, as shown in Fig. 2, is shown. While said box could be variously formed, in the embodiment of the invention illustrated said box is preferably formed of sheet material, such as cardboard, stiff paper, etc., and is folded from a blank 10a, one form of which is shown in Fig. 3. This blank is of substantially rectangular form and will be folded along spaced parallel lines 10b spaced equally from the longitudinal sides of said blank. Blank 10a is also foldable about spaced transverse lines 10c extending at right angles to lines 10b and to the sides of said blank, the distance between lines 10b and 10c determining the width and thickness of the box. The blank will be cut along the lines 10c at the portions thereof outside of lines 10b. Blank 10a has a narrow zone 10d at one end thereof formed by a transverse line 10e parallel to and spaced a short distance from one end of said blank and the blank will be cut along line 10e at the portions thereof outside of lines 10b. Said blank has another zone 10f adjacent

one end thereof formed by parallel transverse lines $10g$ which extend at right angles to lines $10b$. A zone $10f$ is formed between lines $10g$ and $10b$ which forms the bottom of the box. Zone $10f$ has side portions $10h$ which are foldable along lines $10b$ and which taper outwardly from said lines, the same being provided with notches $10i$ at their outer portions so that said side portions have projections $10j$ and are of hook-like form. Another zone $10k$ is disposed at the opposite end of said blank, the same being formed between the outer line $10g$ and the end of said blank. Zone $10k$ is foldable along lines $10b$ and is also adapted to be folded along a substantially median line $10m$ parallel to lines $10g$. Portion or zone $10k$ is provided with openings $10n$ in its side portions and while these might vary in form, in the embodiment of the invention illustrated they are shown as tapering outwardly from lines $10b$ respectively at equal angles to median line $10m$ and as having short converging portions at their outer ends and re-entrant central pointed portions $10na$ at their outer ends. When zone $10k$ is folded along median line $10m$ the pointed portions $10na$ form hook-like projections, as shown in Figs. 4 to 7. The portions of the blank at the outer sides of lines $10b$ are folded upwardly at right angles and the blank is then folded along lines $10c$ and inner line $10g$ into substantially parallelopiped shape, the portion between lines $10b$ and $10g$ forming the bottom of the box and the portion between lines $10b$ and $10c$ forming the top of the box. Zone $10k$ is folded along median line $10m$ in a direction opposite to the folding of the box along the other transverse lines so that a portion is formed of double thickness and when this portion is folded along line $10g$ it extends at right angles to outer line $10g$. It will be noted that the distance between $10e$ and the adjacent line $10c$ is shorter than the distance between inner line $10g$ and the adjacent line $10c$. When the box is folded into parallelopiped form an opening is thus formed in one side of the box, as shown at $10o$ in Figs. 6 and 7. This opening extends across the box and is of course of rectangular form and is adjacent bottom portion $10p$, which, as before stated, is the portion between lines $10g$ and $10b$. The side portions $10h$ of zone $10f$ may be made of greater length outside of lines $10b$ than the rest of the blank, as shown in Fig. 3, although this is not necessary or essential. The portion of the zone $10k$ is folded along its median line $10m$ downwardly or in a direction away from the plane of Fig. 3 so that this zone then becomes of double thickness, as shown in Figs. 6 and 7. When so folded the openings $10n$ form the hook-like portions $10q$, as shown in Figs. 6 and 7. The width of zone $10k$ when so reversely folded is substantially the same as the width of the opening in the front of the box above described so that the portion of zone $10k$ between lines $10b$ closes said opening, as shown in Fig. 5. The narrow zone $10d$ is reversely folded upwardly and this zone is severed outside of lines $10b$ so that its end portions form strips $10r$. When zone $10f$ is folded and the bottom of the box brought to horizontal position, the side portions $10h$ extend along the opposite sides of the box at the outer side thereof and within the strips $10r$. When zone $10k$ is folded upwardly to close opening $10o$, its side portions outside of lines $10b$ also extend along the opposite sides of the box at the outside thereof and these are disposed preferably inside of side portions $10h$, as shown in

Figs. 1 and 4. When the box is in final form the ends of the strips $10r$ are connected by a strip 11 formed of adhesive tape or similar material which extends across the rear of the box and overlaps the strips $10r$, as shown in Fig. 1. Also when the box is in final form a strip 12 is placed across the front of the box covering the slit or crack between the upper portion of zone $10k$ and the lower portion of the reversely folded zone $10d$. This strip may have a thread 13 therein or in the rear thereof opposite said slit or crack so that it can be pulled upon to slit the strip 13 and expose said slit or crack.

In operation when the box is packed or filled with the articles it is to contain, such as screws, it will be in the form shown in Figs. 1, 4 and 5. When the box is to be used for displaying and rendering the contained articles accessible, the strip 13 will be severed as above described and bottom portion or zone $10f$ will then be swung downwardly about its rear side or the line $10g$ remote from the end of the blank and the hook-like portions on the side portions $10h$ will swing forwardly and strike the zone $10d$ at the corners of the box, the side portions moving within the side portions $10i$ of said zone $10d$. The bottom of the box is then brought to the position shown in Fig. 6 and is positively held in this position by side portions $10h$ and strips $10r$. To give greater accessibility to the articles, the zone $10k$ can now be swung downwardly about the outer line $10g$ and when this is done the side portions thereof swing forwardly until the hook-like ends $10q$ engage strips $10r$, as shown in Fig. 7. The articles in the box will now drop down on the bottom and on the top of zone $10k$ and will be plainly visible and can be easily picked out of the box. The box can be arranged to be suspended in vertical position on a support when it will occupy the position shown in Fig. 7 or it can be rested upon the bottom formed by zone $10f$ and in which position zone $10k$ would extend upwardly at a greater angle, as shown in Fig. 7. The weight of the contents of the box will hold the same in stable position on the bottom. It is not necessary to have the hook portions on zone $10k$ as the side portions thereof will very solidly and firmly engage zone $10d$ and hold the zone $10k$ in proper position.

From the above description it will be seen that I have provided a comparatively simple structure of box for screws, tacks and other articles which can very readily be placed in condition to make the articles visible and accessible. The device will have a high degree of utility in stores and the boxes containing various sizes of articles can be arranged in a row or rows so that the articles can be very quickly seen and removed when desired. The blank can be very easily and quickly cut with the proper die just as a blank for an ordinary box can be cut. The folding of the box can be very rapidly performed. The box is in very secure condition for shipment and as above described it is but a moment's work to place the same in condition to render the articles visible and accessible. The device has been amply tested in actual practice and found to be very successful and efficient.

It will of course be understood that various changes may be made in the form, details, arrangement and proportions of the parts, without departing from the scope of applicant's invention, which generally stated, consists in a device capable of carrying out the objects above set forth, in the parts and combinations of parts

disclosed and defined in the appended claims.

What is claimed is:

1. A box made of folded sheet material, the same being rectangular in transverse cross section and having a bottom portion swingable downwardly about one edge thereof, said box having an opening adjacent said bottom in the side opposite said edge, said bottom having side portions extending upwardly therefrom and having a front portion extending upwardly therefrom adapted to close said opening when said box is in closed position, and means on said box engaged by said side portions for holding said bottom in downwardly swung position, said front portion being swingable about the edge of said bottom opposite said first mentioned edge, and means for holding said front portion in swung position.

2. A box made of sheet material and being substantially rectangular in transverse cross section, the same having a bottom swingable about a line parallel to one side of said box when said box is in folded operative position, said box having an opening adjacent said bottom at the opposite side, said bottom having side portions extending upwardly therefrom at opposite sides of said box and having a front portion extending upwardly therefrom adapted to close said opening, and means for holding said bottom in downwardly swung position whereby articles can be shipped in said box when closed and displayed and dispensed from said box when said opening is exposed.

3. The structure set forth in claim 2, said front portion having side portions extending therefrom along the sides of said box, and means engaged by said side portions of said front portion for holding said front portion in swung position.

4. A box made from folded sheet material, the same being rectangular in transverse cross section and having a bottom swingable about one edge thereof, said box having an opening adjacent said bottom at the side opposite said edge, said bottom having side portions extending upwardly therefrom and disposed at opposite sides of said box, said bottom having a front portion swingable about the edge of said bottom opposite said first mentioned edge and adapted to close said opening when said box is in closed position, bands extending along said opposite sides of said box and said side portions having projections adapted to engage said bands respectively to hold said bottom in downwardly swung position, said front portion having side extensions also adapted to engage said bands to hold said front portion in swung position.

5. The structure set forth in claim 4, said front portion and said side extensions being folded about a transverse substantially median line so as to be of double thickness.

6. A box made from folded sheet material, the same being rectangular in transverse cross section and having a bottom swingable about one edge thereof, said box having an opening adjacent said bottom at the side opposite said edge, said bottom having side portions extending upwardly therefrom and disposed at opposite sides of said box, said bottom having a front portion swingable about the edge of said bottom opposite said first mentioned edge and adapted to close said opening when said box is in closed position, members disposed at opposite sides of said box, said side portions being notched to form hook-like projections adapted to engage said

members respectively to hold said bottom in downwardly swung position.

7. The structure set forth in claim 6, and side portions extending from said front portion also disposed at the sides of said box and adapted to respectively engage said members to hold said front portion in swung position.

8. A blank adapted to be folded to make a box of parallelopiped form, said blank being of general rectangular form and being foldable along spaced parallel lines extending longitudinally thereof and throughout the length thereof and equally spaced from the sides thereof, said blank being foldable about spaced parallel transverse lines, said blank having a zone at one end foldable about the line connecting it with said blank to form the bottom of said box, said zone having side portions foldable about said first mentioned lines and an end zone foldable about the line connecting it with said first mentioned zone and having side portions foldable about said first mentioned lines.

9. The structure set forth in claim 8, said side portions of said first mentioned zone tapering outwardly and being notched to have hook-like projections at their outer sides.

10. A blank adapted to be folded to make a box of parallelopiped form, said blank being of general rectangular form and being foldable along spaced parallel lines extending longitudinally thereof and throughout the length thereof and equally spaced from the sides thereof, said blank being foldable about spaced parallel transverse lines, said blank having a zone at one end foldable about the line connecting it with said blank to form the bottom of said box, said zone having side portions foldable about said first mentioned lines and an end zone foldable about the line connecting it with said first mentioned zone and having side portions foldable about said first mentioned lines, said last mentioned zone being foldable about a transverse substantially median line and having openings in its side portions, said opening tapering outwardly from a point on said first mentioned lines respectively and having re-entrant central pointed portions, said openings being symmetrical about said median line so that hook-like projections are formed when said zone is folded along said median line.

11. A box of sheet material of rectangular shape in cross section, the same having a bottom secured thereto against bodily movement swingable about one side thereof, said bottom having a portion extending upwardly at the opposite side thereof substantially at right angles thereto, said portion forming part of the last mentioned side of said box and closing said last mentioned side so that when said bottom is swung downwardly about said first mentioned side an opening is formed in said second mentioned side of said box by said swinging movement between the upper edge of said portion and the edge of the adjacent portion of said last mentioned side thereabove through which the contents of said box are visible and may be accessible, means for holding said bottom in said swung position whereby articles may be shipped in said box when in closed position and may be dispensed therefrom when said bottom is swung downwardly, said first mentioned portion being swingable about the edge opposite said first mentioned edge to further enlarge said opening, and means for holding said first mentioned portion in said swung position.

12. A box made of sheet material and of rec-

tangular shape in cross section having a bottom swingable about one edge thereof when said box is in folded operative position, said bottom having side portions extending upwardly therefrom and having a front portion extending upwardly therefrom, said box having an opening in one side closable by said front portion, said opening being exposed when said bottom swings downwardly about said edge, means engaged by said side portions for holding said bottom in swung position to expose said opening, said front portion being swingable about the edge opposite said first mentioned edge, side portions extending along the sides of said box connected to said front portion, and means engaged by said last mentioned side portions for holding said front portion in swung position, whereby small articles may be shipped in said box when closed and may be displayed and dispensed therefrom when said opening is exposed.

13. A box made of sheet material and of general parallelopiped form having in combination, top, side, rear and front walls and a bottom, said front wall having a transverse division some distance above said bottom, the portion below said division being connected to said bottom, said bottom having portions connecting to the sides thereof extending upwardly along said side walls

respectively, means for holding said bottom and portions in place with the box in closed condition, said bottom and the portions being swingable downwardly about the rear edge of said bottom when released from said means whereby a trough-like structure is formed having an opening thereabove into the front of said box, said last mentioned portions engaging said front wall to limit said downwardly swinging movement of said box, said first mentioned portion being swingable forwardly further about its lower edge, and means for limiting said swinging movement thereof.
